UNITED STATES PATENT OFFICE.

GLENN W. TRAER, OF CHICAGO, ILLINOIS.

COAL-CARRIER FOR RETORTS.

1,267,479.

Specification of Letters Patent. Patented May 28, 1918.

Application filed March 10, 1917. Serial No. 153,911.

To all whom it may concern:

Be it known that I, GLENN W. TRAER, a citizen of the United States, and a resident of Chicago, in the county of Cook and State of Illinois, have invented certain new and useful Improvements in Coal-Carriers for Retorts, of which the following is a description, reference being had to the accompanying drawings, which form a part of my specification.

My invention relates more particularly to a movable coal container or carrier adapted for use in a retort or "oven" for distilling the volatile hydrocarbons from coal, more especially bituminous coal, at temperatures greatly less than are employed in the ordinary gas-house and by-product ovens for making non-volatile coke; my improved carrier or container being especially designed to convey coal through a retort or oven having coking and cooling chambers, thus enabling a substantially continuous coking method to be employed.

The invention contemplates means whereby the coal will be maintained in the retort in columnar units of greater vertical than transverse dimensions, in order that the heat will be more or less uniformly transmitted through the body of the coal, which is preferably arranged in predetermined and separated quantities, at the various points in the coking oven or chamber while the coal travels from the inlet or charging end toward the outlet or discharging end of the retort; the invention contemplates means of great heat conductivity, for holding the predetermined quantities of coal, adapted to freely travel through the coking oven or chamber and thereby overcoming the difficulties heretofore encountered through the natural tendency of the coal, while in a plastic state, to expand against the sides of the oven or chamber in such manner as to impede and prevent its easy movement through the oven or coking chamber; the means being of such construction that the coked coal may be readily discharged therefrom upon the withdrawal of the respective containers from the retort.

The advantages of the invention will be more fully comprehended from the follow-

ing detailed description of the accompanying drawing, wherein:—

Figure 1 illustrates my improved carrier in side elevation. 55

Fig. 2 is a top plan view of same.

Fig. 3 is a vertical sectional view.

My invention, as previously stated, is especially intended for carrying or conveying coal, and the resultant coke, in separated columnar quantities through a suitable retort provided with coking and cooling chambers; and in the particular exemplification, it comprises a metallic receptacle having four sides 5, 6, 7 and 8; with the two sides, 5 and 6, of greater lateral dimensions than the sides 7 and 8, so as to provide a carrier of greater vertical and longitudinal dimensions than the transverse dimensions thereof; in other words, to provide a carrier 70 of considerable height, but of comparative narrow dimensions.

The container or carrier is composed of metal of great heat conductivity, open at its top, see Figs. 2 and 3, and provided with a removable bottom 9, hinged at the one end, as shown at 10, to the lower end of a link 11 which is pivotally secured at 12 to a lug or boss 13 formed on the end wall 8 of the container. 80

The bottom 9 is preferably provided with upwardly presented flange portions 14 extending about the entire bottom so as to overlap the lower portions of the side walls of the container. The free end of the bottom 85 is provided with a pawl 15 pivoted to the bottom at 16 and disposed upwardly to engage with a lug 17 secured at the forward end of the container, thus providing a suitable latch for holding the bottom in closed 90 position.

The container is provided with a number of transversely disposed metallic partitions 18, formed and secured in any suitable manner to the side walls 5 and 6 whereby the container is divided into a plurality of vertically disposed compartments, so that the coal will be maintained in a plurality of comparatively thin vertical columns, which will not only enable the coke to be more 100 readily released from the container, but will also induce a more rapid coking or distilla-

tion of the coal, by reason of the heat conductivity of the metal of which the walls of the container as well as the intermediate partitions are composed. With this construction, the coal is divided into a number of narrow columns disposed transversely and entirely across the carriers; the comparatively thin columns of coal being surrounded on all sides by heat-conducting metallic walls which not only enhance the distillation of the coal, but cause a more thorough coking of the entire mass or individual columns, without subjecting the outer layers of coal, namely the sides of the different columns, to such degree of heat as would distil all the hydrocarbons therefrom.

In order that the containers may be induced to travel more smoothly and freely, through the chambers of a retort or oven, I prefer to provide both ends of the container, in proximity to the side walls thereof, with rollers 19 disclosed vertically and trunnioned in suitable brackets 20 secured on the end walls of the container; the rollers being so mounted as to extend slightly beyond the plane of the side walls of the container and in advance thereof so as to engage with the side walls of the oven and thereby prevent the possibility of the corners of the metallic container wedging against the side walls of the oven. For convenience in handling, both end walls of the container are also shown provided with suitable handles or grappling portions 21.

The bottom 9 of the container is also shown preferably provided with rollers 22 at opposite ends thereof; the rollers 22 at the forward ends of the container may be journaled on the pivot 16 of pawl 15, while the rollers 22 at the rear ends are shown journaled on the pivots 10 for the bottom 9. These rollers permit the container to be moved readily from place to place and through the chambers of the retort or oven.

In providing the carriers herein shown and described, a positive method of handling the coal, while in a plastic state in the distillation portion or coking chamber of an oven, is provided, and "plugging" of the oven will be prevented; at the same time a continuous retort or coking method is obtained through the use of a suitable number of carriers which may be successively inserted into the oven.

I have shown and described what I believe to be the best embodiment of my invention, but certain details of construction may be modified without, however, departing from the spirit of the invention.

60 What I claim is:—

1. A coal carrier of the class described, comprising an elongated metallic container of greater vertical dimensions than trans-

verse dimensions so as to provide a comparatively narrow column of coal, and a bottom hinged at one end and provided with rollers at both ends thereof.

2. A coal carrier of the class described, comprising a metallic container, rectangular in cross-section and of greater longitudinal and vertical dimensions than the transverse dimension thereof, said container being provided with an open top, a plurality of metallic partitions extending from top to bottom and disposed from side to side whereby the carrier is divided into a number of narrow vertically disposed chambers, a metallic bottom pivotally secured so as to swing downwardly, and means whereby the free end of the bottom is removably held in closed position.

3. A coal carrier of the class described, comprising a rectangular container composed of heat-conducting material, said container being of greater vertical dimension than the transverse dimension thereof, a series of partitions of heat-conducting material disposed from top to bottom and extending from side to side in the container and secured thereto whereby the container is divided into a series of vertically disposed narrow chambers, the side walls whereof are formed by the side walls of the container, a bottom for said container pivotally secured at one end so as to swing from beneath the container, and a pivoted latch member whereby the free end of the bottom is held in closed position.

4. A coal carrier of the class described, comprising a metallic rectangular container of greater vertical dimension than the transverse dimension thereof, a metallic bottom pivotally secured at one end to the wall of the container so as to swing from beneath the container, means whereby the free end of the bottom is latched in closed position, and anti-friction members mounted at opposite ends of the container so as to extend forward of the respective end walls of the container.

5. A coal carrier of the class described, comprising a metallic container, rectangular in cross-section and of greater vertical dimension than the transverse dimension thereof, a plurality of metallic partitions disposed from top to bottom and from side to side of the container whereby the container is divided into a series of narrow vertically disposed compartments whose sides are formed by the side walls of the container, a metallic bottom pivotally secured at one end of the container and provided with anti-friction bearings at both ends thereof, a pivotally secured latch member whereby the free end of the bottom is held in closed position, and anti-friction means

rotatably mounted on the end walls of the container so as to be disposed in advance of said end walls.

6. A coal carrier of the class described, comprising a rectangular metallic container of greater vertical dimension than the transverse dimension thereof and open at its top, a plurality of metallic partitions extending from top to bottom and from side to side of

the container whereby the coal in the container is divided into narrow vertically disposed columns, and a removable metallic bottom.
